US00D382914S

United States Patent

[19]

Ho et al.

[11] Patent Number: Des. 382,914

[45] Date of Patent: **Aug. 26, 1997

[54] ELECTRONIC GAME HOUSING

[75] Inventors: **To-Ling Ho**, North Point; **Siu Fai Au Yeung**, Kowloon, both of Hong Kong[73] Assignee: **Tiger Electronics, Inc.**, Vernon Hills, Ill.

[**] Term: 14 Years

[21] Appl. No.: 48,953

[22] Filed: Jan. 16, 1996

[51] LOC (6) Cl. 21-01

[52] U.S. Cl. D21/13

[58] Field of Search ..... D21/1, 13, 48; 273/148 B; 463/30-35, 43-47
